CABLE CORING TOOL

James J. Matthews, East Haddam, Conn., assignor to
Utility Tool Corp., East Haddam, Conn.

Filed Apr. 4, 1973, Ser. No. 347,862

Term of patent 14 years

Int. Cl. D8—03

U.S. Cl. D8—98

FIG. 1 is a top plan view of a cable coring tool according to my invention;

FIG. 2 is a side elevational view of the cable coring tool shown in FIG. 1;

FIG. 3 is an end view of the tool shown in FIG. 1, looking from the right;

FIG. 4 is an end view of the tool shown in FIG. 1 looking from the left;

FIG. 5 is a sectional view taken along the line 5—5 of FIG. 2;

FIG. 6 is a top plan view of the cable coring tool shown in FIG. 1 in a retracted position;

FIG. 7 is a bottom view of a cable coring tool, similar to the cable coring tool of FIG. 1; showing an alternate embodiment of the cutter portion;

FIG. 8 is a fragmentary side elevational view of the tool shown in FIG. 7, and

FIG. 9 is an end view of the cable coring tool of FIG. 7, looking from the left.

I claim:

The ornamental design for a cable coring tool, as shown and described herein.
